CLAIM

The ornamental design for a convertible storage bin with lid, as shown and described.

DESCRIPTION

FIG. 1 is a perspective view of a storage bin and lid showing my new design.

FIG. 2 is an exploded perspective view of the storage bin and lid shown in FIG. 1 with the lid removed from the storage bin.

FIG. 3 is a top view of the storage bin and lid shown in FIG. 1.

FIG. 4 is a bottom view of the storage bin and lid shown in FIG. 1.

FIG. 5 is a side view of the storage bin and lid shown in FIG. 1; the opposite side being a mirror image thereof.

FIG. 6 is an end view of the storage bin and lid shown in FIG. 1; the opposite end being a mirror image thereof.

FIG. 7 is a perspective view of the storage bin only shown in FIG. 1 in a partially unfolded configuration.

FIG. 8 is a perspective view of the storage bin shown in FIG. 7 in a flattened configuration; and,

FIG. 9 is a top view of the storage bin shown in FIG. 8 in the flattened configuration.

All broken lines, including stitching lines and fold lines, are illustrative of environment and form no part of the claimed design.
